COIN CHUTE

Clyde B. Gorton, Chicago, Ill., assignor to
C. B. McClellan, Chicago, Ill.

Original application September 6, 1934, Serial
No. 742,885. Divided and this application Jan-
uary 7, 1935, Serial No. 617

5 Claims. (Cl. 194—98)

This invention relates to a coin chute.

This application is a division of application Serial No. 742,885, filed September 6, 1934, Patent No. 1,987,292, dated January 8, 1935.

5 It is an object of this invention to provide an improved coin chute which is relatively simple and inexpensive in construction and efficient in use.

Another object of the invention is to provide a 10 new and improved coin chute adapted for use in conjunction with any coin controlled device or machine, such, for example, as vending machines, amusement game apparatus, etc.

An additional object of the invention is to provide 15 a coin chute which is constructed in such a manner that when a coin is inserted into the coin chute to operate an amusement game apparatus, vending device, or other mechanism associated therewith, the coin is moved into a coin-receiving 20 and displaying receptacle and is therein exposed through a sight opening to the view of the proprietor or owner of the amusement apparatus or vending device with which the coin chute is associated so that the proprietor may readily ascertain 25 whether or not the player or operator of the device has inserted a proper coin into the chute to operate same.

Other objects will appear hereinafter.

The invention consists in the novel combination 30 and arrangement of parts to be hereinafter described and claimed.

The invention will be best understood by reference to the accompanying drawing, showing the preferred form of construction and in which:

35 Fig. 1 is an elevational view of a coin chute embodying the invention;

Fig. 2 is a top plan view of the same showing the coin slide and associated parts in coin-receiving position;

40 Fig. 3 is a sectional view on line 3—3 in Fig. 2 but showing the coin slide and associated parts in full stroke position;

Fig. 4 is a fragmentary top plan view of an 45 amusement game cabinet showing the new coin chute associated therewith; and

Fig. 5 is a fragmentary sectional view on line 5—5 in Fig. 1.

A preferred embodiment of the new coin chute 50 is shown in the drawing, is generally indicated therein at 10, and includes a guide structure 11 and a coin slide carried thereby and generally indicated at 12, and the coin slide 12 includes two parts 13 and 14 which are substantially similar 55 in construction.

Formed in the coin slide 12, partly in each of the two coin slide parts 13 and 14, is a coin-receiving pocket 15 (Fig. 5) and communicating at its lower end with this coin-receiving pocket 15, when the coin slide 12 is in coin-receiving position, as in Figs. 1 and 2, is a coin chute 16. 5

Arranged within a pocket 17 provided therefor in the coin slide member 14 is a pivoted latch dog 18 (Fig. 5); one end portion of the latch dog 18 being normally projected into a slot 19 which is 10 formed in a wall 20 of the guide 11 (Fig. 5) by the action of a spring 21 which is arranged in a pocket 22 provided therefor in the coin slide member 14 (Fig. 5).

15 Mounted on the top wall of the guide 11 is a coin-displaying receptacle in the form of a pan 23 and when the coin chute is in operative position, as in Fig. 4, this receptacle 23 is visible 20 through a sight opening 24 provided therefor in the top wall 25 of the cabinet 26 of the game apparatus with which the new coin chute is shown associated, for the purpose of illustrating its use.

The coin display receptacle 23 is provided with a discharge opening 27 and provided in the bottom wall of the display pan or receptacle 23 is a vertical slot 28 (Fig. 2) into which projects an upwardly extending arm 29 of a coin ejecting member 30, the coin ejecting member 30 being provided with a horizontal slot 31 into which projects a lateral extension or pin 32, the pin or extension 32 projecting from the side wall of the guide 11. This coin ejecting member 30 has a hooked or latching end portion 33 which is latchingly engageable with a latch pin 34 which projects from the wall of the coin slide member 14. 35 Formed on the coin ejecting member 30 is a cam surface 35 and projecting laterally from the guide 11 is a pin 36 with which the cam surface 35 engages when the coin ejector 30 is moved (left to right, Figs. 1, 2 and 3). 40

Pivotedly mounted on the bottom wall of the guide 11, as at 37, is a coin ejector 38 which has an upwardly extending arm 39 and this arm 39 projects through a slot 40 formed in the bottom wall of the guide 11 (Fig. 3) into the coin-receiving pocket 15; the coin ejector 38 being urged clockwise, Figs. 1 and 3) by a spring 41. 45

Having one end attached to the guide 11 and having its other end attached to a pin 42 which depends from the coin slide member 14 is a re-setting spring 43. 50

Formed in the bottom wall of the coin receptacle or pan 23 is a slot 44 (Fig. 2) and extending upwardly from the bottom wall of the pan 23 and 55

curved over and above and toward one side of the slot 44 (Fig. 2) is a coin deflector 45.

Operation

5 When a coin of proper denomination, etc., is inserted into the coin chute 16, it falls by gravity down the same into the coin-receiving aperture or pocket 15 formed in the coin slide 12, whereupon the coin slide 12, being urged inwardly (left to right, Figs. 1, 2 and 3) urges the coin which is arranged in the pocket 15, into engagement with the latch dog 18, thereby pivoting the latch dog 18 out of latching engagement with the wall 20 of the guide 11, the wall 20 being the wall of the guide 11 which defines the slot 19 into which one end portion of the latch dog 18 normally is urged by action of the spring 21 which is arranged in the pocket 22 provided therefor in the coin slide members 13 and 14, thus forcing the latch dog 18 out of latching engagement with the wall 20 of the guide 11 in which the slot 19 is formed (Fig. 5).

At the beginning of the inward stroke of the coin slide 12 that is, when the coin slide 12 is in the position of Figs. 1 and 2, the coin pocket 15 is disposed out of registration with the slot 44, (being to the left of the same as seen in Figs. 1 and 2) and the coin ejecting member 29-30 is disposed in the full line position of Fig. 1. However, when the coin slide 12 is moved inwardly (left to right, Figs. 1, 2, 3 and 5), the coin in the pocket 15 engages the upwardly extending arm 39 of the coin ejecting member 38 and urges the latter (counterclockwise into dotted line position, Figs. 1 and 3), but during this inward stroke of the coin slide 12 the manual pressure exerted by the operator of the slide upon the same urges the two coin slide parts or members 13 and 14 together and, in so doing, jams the coin in the coin pocket 15, thereby preventing the coin from being ejected from the coin pocket 15 until the slide has completed its full inward stroke and the manual pressure exerted by the operator is released, whereupon the coin slide 12 is retracted (right to left, Figs. 1, 2, 3 and 5) by its resetting spring 43. During this return stroke of the slide 12 the spring 41 urges the coin-ejecting member 38-39 (from dotted to full line position, Fig. 1), thus forcing the projecting portion 39 of the coin-ejecting member 38 up through the slot 40 and coin pocket 15 into the slot 44 and thereby ejecting the coin out of the coin pocket 15 of the coin slide 12 up through the slot 44, which is formed in the bottom wall of the display receptacle 23, and the coin thus ejected from the coin pocket 15 through the slot 44 is deflected by the deflector member 45 onto the bottom wall of the receptacle 23 into position "A", Fig. 2, and is held exposed to public view through the sight opening 24 in the cabinet 26 so that the proprietor of the game apparatus or other coin-controlled device, with which the coin chute 10 is associated may readily see the coin thus exposed to view and thereby determine whether or not the player of the device or apparatus has inserted a coin of the proper denomination into the coin chute 16 or has attempted to operate the same fraudulently, as the case may be.

The coin 46 thus ejected into the coin receptacle 23 remains therein, in position "A" (Fig. 2), until another coin of proper denomination, size, etc., is inserted into the coin chute 16 and coin pocket 15 and the coin slide 12 is again operated, whereupon the upwardly projecting portion 29 of the coin ejecting member 30, being moved through the slot 28 which is formed in the bottom wall of the coin display receptacle 23 (left to right, from full to

dotted line position, Fig. 1), engages behind the last coin 46 deposited in the display receptacle 23, in position "A", and in so doing, forces the coin 46 from position "A", around the inside of the curved vertical wall 47 of the display receptacle 23 (counterclockwise, in the direction of the arrow, Fig. 2) and in this manner ejects the coin from position "A" out through the discharge opening 27 of the coin display receptacle 23 into any suitable coin-holding receptacle which may be provided therefor in the cabinet 26 of the game apparatus or other coin-controlled device with which the coin chute 10 may be associated.

At this time the cam surface 35 of the coin ejecting member 29-30 engages the pin 36 and thereby pivots the coin ejecting and latch member 29-30 (counterclockwise, from full to dotted line position Fig. 1), thus lifting the hooked end portion 33 of the member 29-30 up out of latching engagement with the latch pin 34 whereupon a tensioned spring 48 retracts or jerks the coin ejecting member 29-30 back into its initial position (as in full lines, Fig. 1). The coin slide 12 then continues its movement from left to right (Fig. 1) to the full stroke position (as in Fig. 3), whereupon the coin carried by the slide 12 is ejected by the coin ejecting member 38-39 from the coin pocket 15 up through the slot 44 into position "A" in the coin-receptacle 23, wherein it is held until the foregoing cycle of operations is begun over again and the last coin deposited in the coin receptacle 23 is ejected therefrom, from position "A", out through the discharge opening 27, in the manner hereinbefore explained; the coin slide 12 is then retracted into coin-receiving position by its resetting spring 43. During this movement the coin slide part 13 is reset into its initial position by the action of a resetting coil spring 50, one end of which is attached, as at 51, to the coin slide part 13, and the other end of which is attached 40 to the wall 26, as shown in Fig. 3.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims. 50

I claim:

1. A coin chute comprising the combination of: a guide; a coin slide carried by the guide having a coin-receiving or token-receiving pocket formed therein; a coin receptacle arranged on one side of the guide and slide; means including a pivotal member arranged on the opposite side of the guide and coacting with said slide when the latter is moved in one direction to eject a coin from said coin pocket into said coin receptacle; and means including a slidable member coacting with the said coin slide to eject a coin from said coin receptacle when the said coin slide is moved in a direction opposite to the said first-named direction. 65

2. A coin chute comprising the combination of: a guide; a coin slide carried by the said guide having a coin-receiving or token-receiving pocket formed therein; a coin display receptacle arranged above the said coin slide and over the said guide; means including a pivotal member arranged below the said coin display receptacle and coacting with the said coin slide when the latter is moved in one direction to eject a coin from the said coin pocket into said receptacle; and 70

means including a slidable member coacting with the said coin slide to eject a coin from said coin receptacle when the said coin slide is moved in a direction opposite to the said first-named direction.

- 5 3. A coin chute comprising the combination of: a guide; a coin slide carried by the said guide and having a coin-receiving recess or pocket formed therein; a coin display receptacle arranged above the said slide and over the said guide and having a bottom wall extending in a plane substantially parallel to, but above, the plane of movement of the said coin slide; means coacting with the said coin slide to eject a coin from the said pocket into the said coin display receptacle; means in said coin display receptacle for deflecting a coin ejected from said coin pocket into said coin display receptacle in such a manner that the coin thus ejected into said coin display receptacle will be positioned therein with its flat face resting upon the said bottom wall of said coin display receptacle; and means coacting with the said coin slide to eject coins one at a time from said coin display receptacle.
- 10 4. A coin chute comprising the combination of: a guide; a coin slide carried by the said guide and having a coin-receiving recess or pocket formed therein; a coin display receptacle arranged on one side the said guide and having a
- 15 20 25

bottom wall extending in a plane substantially parallel to, the plane of movement of the said coin slide; means coacting with the said coin slide to eject a coin from the said pocket into the said coin display receptacle; means in said coin display receptacle for deflecting a coin ejected from said coin pocket into said coin display receptacle in such a manner that the coin thus ejected into said coin display receptacle will be positioned therein with its flat face resting upon the said bottom wall of said coin display receptacle; and means coacting with the said coin slide to eject coins one at a time from said coin display receptacle.

5 15 20 25

5. A coin chute comprising the combination of: a guide; a coin slide carried by the guide having a coin-receiving or token-receiving pocket formed therein; a coin receptacle arranged on one side of the guide and slide; means including a spring actuated member arranged on the opposite side of the guide and coacting with said slide when the latter is moved in one direction to eject a coin from said coin pocket into said coin receptacle; and means including a slidable member coacting with the said coin slide to eject a coin from said coin receptacle when the said coin slide is moved in a direction opposite to the said first-named direction.

CLYDE B. GORTON.
